United States Patent

Des. 235,430
Patented June 17, 1975

235,430

MOTORCYCLE WHEEL

Delmer D. Scott, Encino, Calif., assignor to Shelby Dowd
Industries, Inc., Marina Del Rey, Calif.

Filed Mar. 25, 1974, Ser. No. 454,226

Term of patent 14 years

Int. Cl. D12—16

U.S. Cl. D12—205

FIG. 1 is a front elevational view of a motorcycle wheel showing my new design;

FIG. 2 is a rear elevational view thereof;

FIG. 3 is a side elevational view thereof; and

FIG. 4 is a cross-sectional view thereof taken on the line 4—4 of FIG. 1.

I claim:

The ornamental design for a motorcycle wheel, as shown.
